INTERNAL COMBUSTION ENGINE

Carl C. Ottoson, Port Richmond, N. Y.

Application July 15, 1933, Serial No. 680,585

9 Claims.

(Cl. 123—47)

This invention relates to improvements in internal combustion engines; and the invention has reference, more particularly, to a novel construction of low weight, high speed internal combustion engine of the four cycle type adapted to operate on either gasoline or on low grade fuels, such as light furnace oils, light distillates, etc.

This invention has for its general object to provide a novel construction of four cycle internal combustion engine having a two-step piston, comprising upper and lower sections respectively reciprocating in corresponding upper and lower cylinder sections or chambers, together with a novel valve arrangement whereby air admission is controlled, and timed delivery of admitted air to the firing chamber during proper cycles of piston movement is attained for scavenging and cooling effects and for producing a combustible fuel mixture of high efficiency.

Other and more specific objects of this invention, not at this time more particularly enumerated, will be understood from the following detailed description of the same.

An illustrative embodiment of this invention is shown in the accompanying drawings, in which:

Fig. 1 is a side elevation of an internal combustion engine according to this invention, the lower part of the crank-case and parts of the gear housing being removed; Fig. 2 is a transverse vertical section, taken on line 2—2 in Fig. 1.

Figs. 3, 4, 5 and 6 are respectively diagrammatic or schematic views illustrating the piston and valve operation of the engine during the several cycles of piston movement.

Fig. 7 is a fragmentary transverse vertical section illustrating a modified form of piston air by-pass valve and actuating means therefor.

Similar characters of reference are employed in the above described views, to indicate corresponding parts.

To simplify illustration the principles of this invention are shown in the above described views as embodied in a single cylinder engine, but it will be understood that novel arrangements and constructions are equally applicable to engines of the multi-cylinder type.

Referring to said drawings, the reference character 10 indicates the cylinder block which is bored to provide an upper or firing chamber section 11 and a lower or air chamber section 12, the latter of enlarged diameter comparative to the former. Suitably secured to the upper end of the cylinder block 10 is a cylinder head 13.

Suitably secured to the lower end of the cylinder block 10 is a crank-casing 14, in which is journaled a crank-shaft 15.

Connected with the cylinder block 10 for communication with the air chamber section 12 is a valve housing 16, the same having an exteriorly opening air admission port 17 through which is admitted air for scavenging and cooling effects, and which, for purposes of distinction from other air admission means, will be hereinafter referred to as the primary air port. At the inner end of said primary air port 17 is provided a valve seat 18 to receive a primary air valve 19, preferably of the poppet type, i. e. spring-urged to a normally closed position.

Also connected with the cylinder block 10 for communication with the air chamber section 12 is a valve housing 20, the same having an air admission port 21 through which air is admitted for fuel admixture purposes, and which, for purposes of distinction from said scavenging and cooling air admission port 17, will be hereinafter referred to as the secondary air port. At the inner end of said secondary air port 21 is provided a valve seat 22 to receive a secondary air valve 23, which is also preferably of the poppet type, i. e. spring-urged to a normally closed position. Connected with the outer end of said secondary air port 21 is an intake duct 24 provided in the passage thereof with a manipulatable control or throttle valve 25 for varying at will the volume of air admitted through the secondary air port 21 upon opening of the valve 23.

Connected with the cylinder head 13 for communication with the firing chamber section 11 is a valve housing 26, the same having an outwardly opening exhaust port 27. At the inner end of said exhaust port 27 is provided a valve seat 28 to receive an exhaust valve 29, which is preferably of the poppet type, i. e. spring-urged to a normally closed position.

Arranged for reciprocation within the cylinder block 10 is a two-step piston, comprising an upper section 30 movable in the firing chamber section 11 and a lower section 31 movable in the air chamber section 12. The upper section 30 and lower section 31 of the piston are suitably constructed and assembled together so as to provide intermediate air by-pass or transfer passage 32 which, at its lower end, communicates with the interior of said air chamber section 12 of the cylinder block 10, and which, at its upper end, communicates with an air delivery port 33 in the top of the upper piston section leading into

the firing chamber section 11 of the cylinder block. At the discharge side of said air delivery port 33 is a valve seat 34 to receive an air delivery valve 35, which is preferably of the poppet type, i. e. spring-urged to normally closed position. The stem 36 of said air-delivery valve 35 is slidably mounted in a guide bushing 37 to project into the hollow open lower end portion 38 of the piston so as to terminate above the location of a wrist-pin 39 diametrically extending across the piston.

The piston is operatively connected with the crank portion 15' of the crankshaft 15 by a connecting rod or pitman 40, the upper end or knuckle 40' of which is pivotally engaged with the piston wrist-pin 39. Means are provided for effecting opening movement of the air delivery valve 35 during up-moving cycles of the piston operation. In one form, as shown more particularly in Fig. 2 of the drawings, this means comprises a lift-lever 41 which is pivotally connected to the interior side wall of the piston to extend transversely beneath and in engagement with the lower end of the air delivery valve stem 36. Connected with the knuckle 40' of the connecting rod or pitman 40 is a rocker-arm 42 adapted to be oscillated by certain movements of the latter to impart up-swinging movement to said lift-lever 41 for transmission to said valve stem 36 whereby the air delivery valve 35 is caused to open during up-moving cycles of the piston operation.

Suitably journaled in bearing supports 43, as provided for example in connection with the crank-casing 14, is a camshaft 44 adapted to be driven from the crank-shaft 15 in properly timed relation by transmission gearing 45. Fixed on said cam-shaft 44 is a primary air valve actuating cam 46, a secondary air valve actuating cam 47 and an exhaust valve actuating cam 48. Slidable in a guide 49 is a lift-piece 50 having a foot portion 51 engageable by the primary air valve actuating cam 46; said lift-piece 50 is suitably coupled with the stem 52 of said primary air valve 19. Slidable in a similar guide 53 is a lift-piece 54 having a foot portion 55 engageable by the secondary air valve actuating cam 47; said lift-piece 54 is suitably coupled with the stem 56 of said secondary air valve 23.

The exhaust valve 29 is provided with an outwardly extending exteriorly projecting stem 57, slidable in a guide bushing 58 affixed through a wall of the valve housing 26. Pivotally mounted in connection with a fulcrum post 59 secured exteriorly to the valve housing 26 is a rocker-arm 60, one branch of which operatively engages the exhaust valve stem 57. Slidable in a guide 61 is a lift-piece 62 having a foot portion 63 engageable by the exhaust valve actuating cam 48. Said lift-piece 62 is connected with the branch of said rocker-arm 60 by means of a link-rod 64.

Connected with the cylinder head 13 to communicate with the firing chamber section 11 of the cylinder block 10 is a liquid fuel injector or spray nozzle 65. Timed delivery of liquid fuel into the firing chamber section 11 through said injector or spray nozzle 65 is effected by any suitable form of fuel pump mechanism. Preferably the fuel pump mechanism includes a regulator means for more or less automatically regulating the quantum of liquid fuel charge delivered into the firing chamber section in accordance with varying conditions of engine operation. Illustrative of one arrangement of fuel pump means and regulator therefor, a housing 66 is suitably mounted on a supporting bracket 67 connected

with the upper section of the crank-casing 14. Journaled in connection with this housing is a shaft 68 adapted to be driven from the crank-shaft 15, in proper timed relation thereto, by transmission gearing 69. Affixed upon and rotated by the shaft 68 is a fuel pump actuating cam 70. Connected with said housing 66 is a fuel pump casing 71 having a pump bore 72 in which is slidably movable a spring retracted pump plunger 73 having an external thrust head 74 to cooperate with said actuating cam 70. At the intake end of said pump bore 72 is coupling means 75 and an inwardly opening check-valve 76. A liquid fuel supply conduit 77, leading from any suitable fuel storage reservoir or like source of supply, is connected with said coupling means 75 and through said inwardly opening check-valve 76 in communication with the pump bore 72. Said pump casing 71 is provided with a fuel discharge port 78, cooperative with which is an outwardly opening check-valve 79. Coupled in communication with said discharge port 78, by any suitable coupling means, is a fuel delivery conduit 80 which extends to and is coupled with the injector or spray nozzle 65 so as to deliver the fuel charges thereto. Illustrative of the pump regulator means, there is provided in connection with the housing 66 a diaphragm casing 81, the interior of which is divided by a flexible diaphragm 82 into a lower atmospheric pressure chamber 83 beneath the diaphragm, the wall of which is provided with a port 84 open to the atmosphere, and an upper vacuum or low pressure chamber 85 above the diaphragm, which is connected, through a conduit 86, in communication with the air intake duct 24 at a point intermediate the intake side of the secondary air valve 23 and the manipulatable control or throttle valve 25 for purposes to be subsequently set forth. Connected with the center of said diaphragm 82 is a plunger rod comprising an upper section 87 slidably movable in a guide bushing 88 which is carried by an adjusting member 89 threaded to a neck 90 of the diaphragm casing 81. A pressure spring 91 is arranged about the upper section 87 of said plunger rod between the diaphragm 82 and said adjusting member, and is adapted to exert a tensional downward thrust upon the diaphragm and plunger rod. Said plunger rod further comprises a lower section 92 slidably movable in a guideway 93 provided in connection with the wall of the housing 66, whereby the lower end of said plunger rod section 92 enters the interior of said housing 66. Pivotally connected with the extremity of said plunger rod section 92 is an adjusting wedge 94 which lies intermediate the pump actuating cam 70 and pump plunger thrust head 74.

In operation, the engine is designed to effect a four stroke cycle of piston movement, which may be briefly characterized as follows:—

The first stroke constitutes the power and scavenging air intake piston stroke; the second stroke constitutes the exhaust and scavenging and cooling air stroke; the third stroke constitutes, the vacuum, fuel injection and measured fuel air constituent stroke; and the fourth stroke constitutes the compression and fuel and air mixing stroke.

The operations during each piston stroke, and the working of the engine valve system in accordance therewith, will now be successively described, and will be best understood by reference to the schematic views shown in Figs. 3 to 6 of the drawings.

First stroke.—Assuming that the firing cham-

ber section 11 is filled with a combustible fuel mixture, which has been compressed preparatory to firing, the upper and lower piston sections 30 and 31 are disposed at top positions in their respective cylinder sections 11 and 12, during which piston position the measured or secondary air valve 23, the exhaust valve 29 and air delivery valve 35 are closed, with the primary air valve 19 beginning to open (see Fig. 3). Under these conditions the compressed fuel charge is fired by any suitable ignition means, such e. g. as the commonly used electrical ignition spark plug 95. Upon firing of the charge, the piston is driven downward on its power stroke, the respective piston sections 30 and 31 descending respectively in the cylinder chambers 11 and 12. As this piston movement takes place, the primary air valve 19 is timed to open, whereby descent of the piston section 31 draws through the air admission port 17 and into the cylinder air chamber 12 a full unrestricted volume of cool air. By the time the piston completes its downward stroke and reaches bottom center position, the primary air valve 19 closes again. It will thus be seen that a cool air charge is trapped in the cylinder air chamber 12 ready to be transferred through the transfer passages of the upper piston section 30 and air delivery valve 35 into the firing chamber 11 during the next stroke of piston movement, and therein employed for scavenging and cooling effect as will hereafter appear. The capacity of the cylinder air chamber 12 is equal to and may be slightly greater than the upper piston displacement capacity of the firing chamber 11. It will be noted that on the downward stroke of the piston, the pitman 40 will swing to the right, and consequently the rocker-arm 42 will swing downwardly and away from the lift-lever 41, so that no movement is imparted to the latter or to the air delivery valve 35 actuatable thereby and therefore said valve 35 remains closed.

Second stroke.—At the end of the downward movement or power stroke of piston operation, the cylinder firing chamber 11 is filled with spent or burned gases resulting from combustion of the fuel mixture charge, and the cylinder air chamber 12 is filled with a full or maximum charge of cool air. As upward movement of the piston begins, the exhaust valve 29 is timed to open, and as the pitman 40 swings to the left, the rocker-arm 42 will swing upwardly against the lift-lever 41, so that, as the piston moves upward, the lift-lever 41 will be upswung to thereby lift the air delivery valve 35 and thereby open the air delivery port 33 in the piston top during the rising movement of the piston. By virtue of the positions of their controlling actuating cams, the primary air valve 19 and secondary air valve 23 remain closed during the second stroke of piston movement. With the exhaust valve 29 and air delivery valve 35 opened, as the piston rises, its lower section 31 moving upwardly in the cylinder air chamber 12, drives the air previously indrawn and trapped therein, upwardly through the by-pass or transfer passages 32 of the upper piston section 30 and through the open port 33 of the latter into the cylinder firing chamber 11. The cool air is thus caused to sweep through the cylinder firing chamber 11 so as to both drive out through the open exhaust valve 29 the spent or burned gases, while at the same time functioning to reduce the temperature of the piston and the cylinder walls. It will thus be obvious that a very thorough scavenging of the firing chamber is effected, and that the heat resulting from combustion of the fuel mix-

ture charge is quickly and efficiently dissipated.

Third stroke.—At the end of the upward movement or scavenging stroke of piston operation, the piston sections 30—31 arrive at top center of their strokes in the respective cylinder chambers 11 and 12, and again are ready for descent. By the time the pistons are thus positioned, the valve control mechanism has operated to close the exhaust valve 29 and the piston air delivery valve 35, while the primary air valve 19 remains closed. As the piston starts downward, the secondary air valve 23 is timed to open. The downward movement of the upper piston section causes the same to produce a very low pressure (or vacuum) in the cylinder firing chamber 11, which reaches a maximum by the time the piston arrives at bottom center. During the latter part of this downward piston stroke, the injection of liquid fuel through the injector or spray nozzle 65 takes place; the fuel being delivered by the forcing stroke of the pump plunger 73 under the action of the cam 10, which is timed to operatively engage the pump plunger during this period. The downward movement of the lower piston section 31 in the cylinder air chamber 12 during this downward piston stroke, draws into said cylinder air chamber 12 a measured charge of air to be utilized as a constituent of the ultimate fuel mixture. The volume of this fuel mixture air constituent is subject to variation by manipulation of the throttle valve 25; a maximum volume being attained at full open throttle, which may be decreased in proportion to degree of throttle closing down to a minimum volume when the throttle is closed.

Fourth stroke.—Before the piston passes bottom center position, the air valve 23 closes, and as the piston passes bottom center position (the valves 19, 23 and 29 being and remaining closed), the pitman 40 swings to the left and again carries the rocker-arm 42 into up-swinging engagement with the lift-lever 41, so that as the piston moves upward, said lift-lever will raise and open the air delivery valve 35. The rising of the lower piston section 31 in the cylinder air chamber 12 drives the measured volume of air indrawn and trapped therein upwardly through the by-pass or transfer passages 32 of the upper piston section 30 and through the open port 33 into the cylinder firing chamber 11, wherein the thus delivered measured volume of air is mixed with the previously entered liquid fuel constituent to form the ultimate charge of combustible fuel mixture, which is at the same time compressed preparatory to firing by the rising of the upper piston section 30 in the firing chamber 11. By the time the piston reaches top center position, the air delivery valve 35 again closes, compression of the fuel mixture is completed, and repetition of the four strokes of the cycle of operation ensues. As the measured volume of air is delivered into the firing chamber 11 a high degree of turbulence will be induced, due to the difference in pressure in the upper and lower cylinder chambers. This turbulence will be further augmented by the upward movement of the lower piston section 31, and consequently a very thorough intermixing of air and fuel constituents will result. About the time the pistons have reached approximately halfway on their upward stroke, or when an atmospheric equilibrium has been established in both cylinder chambers, compression of the fuel mixture charge begins.

By manipulating the throttle 25 the volume of air to serve as a fuel mixture constituent may

be varied, and the fuel pump regulator will be actuated to effect a proportionate variation of the quantum of liquid fuel delivered by the pump. This latter effect is obtained as follows: With the throttle 25 full open, there is a minimum of restriction to air admission into and through the intake duct 24 under the downward induction stroke of the lower piston section 31, which occurs during the third cycle, and consequently the pressure within low pressure chamber 85 above the diaphragm of the pump regulator is substantially that of the atmosphere and therefore equal to the pressure in chamber 83 below the diaphragm. Under these conditions, the spring 91 exerts a downward thrust upon the plunger rod 87-92, which lowers the adjusting wedge 94 so that its maximum effective thickness is interposed between the pump plunger thrust head 74 and the actuating cam 70, and consequently the full effective stroke of the latter is exerted upon the pump plunger 73 to cause delivery of a maximum charge of liquid fuel through the conduit 80 to the injector or spray nozzle 65. When, however, the throttle 25 is moved toward closed position, the resultant restriction upon air admission into and through the intake duct 24 under the induction stroke of the lower piston section 31, tends to reduce pressure in the low pressure chamber 85 through the communicating conduit 86, and consequently the unbalancing of pressure conditions upon opposite sides of the diaphragm 82, with high or atmospheric pressure effective upon the under side of the latter, tends to raise the diaphragm and plunger 87-92 against the tension of spring 91. This upward movement of the plunger 87-92 withdraws the adjusting wedge 94 so that a portion of reduced thickness is interposed between the pump plunger thrust head 74 and the actuating cam 70. As a consequence of this there is set up lost motion between the cam and the pump plunger which reduces the effective stroke of the latter, and thereby reduces the volume of liquid fuel delivered through the conduit 80 to the injector or spray nozzle 65. It will thus be understood that the volume of fuel mixture is capable of being automatically varied, accordingly as desirable under varying engine operating conditions, by manipulating the throttle 25 which is effective both to reduce the volume of air and liquid fuel constituents of the ultimate fuel mixture charge delivered at any given time to the cylinder firing chamber.

From the above description it will be understood, that a novel internal combustion engine is provided, which operates on a four cycle principle, so as to use an internal flux of cool air for both scavenging and engine cooling effects, and which at the same time is adapted to provide an effective mode of operation as to fuel charge formation, control and compression, which is adaptable to almost any type of fuel mixture, but which is especially advantageous in connection with fuels of the heavier grades.

Referring now to Fig. 7 of the drawings, there is shown therein a modified form of mechanism for actuating the piston air delivery valve 35. In this modified arrangement, instead of the pivoted lift-lever 41 and rocker-arm 42 carried by the pitman 40, there is mounted within the interior of the lower piston section 31 a vertically movable slotted cross-head 96 having an upwardly extending yoke 97, which straddles the pitman knuckle 40, and the sides of which are

slotted as at 98, to straddle the wrist-pin 39. The upper end of this yoke 97 bears on the lower end of the stem 36 of the delivery valve 35. Said cross-head 96 is provided at its lower margins with lift-cam members 99. Mounted on the pitman 40, below the cross-head 96 are rollers 100 which operatively engage said lift-cam members during certain phases of the pitman oscillation, viz. when the pitman 40 swings to the left, the rollers 100 operatively move toward and engage the lift-cam members 99 to impart a rising movement to the cross-head 96, which is in turn transmitted to the air delivery valve stem 36 thereby lifting and opening the valve 35 relative to the port 33 in the top of the upper piston section. These operations occur during the second and fourth strokes of the cycle during upward movement of the piston. During the first and third strokes of the cycle of piston movement, which accord with descending motion of the piston, the pitman oscillates to the right, so that the rollers 100 are carried away from the lift-cam members and consequently no lifting motion is imparted to the cross-head 96 and the air delivery valve 35 remains closed during these cycles. In this modified arrangement, the upper and lower piston sections are shown as cast in an integral piston structure, suitably cored to provide the air bypass or transfer passages 32 leading from the cylinder air chamber 12 to the port 33.

I am aware that various changes may be made in the above described constructions and many apparently widely different embodiments of this invention could be made without departing from the scope thereof as defined in the following claims. It is therefore intended that all matter contained in the above description or shown in the accompanying drawings shall be interpreted as illustrative and not in a limiting sense.

I claim:

1. In an internal combustion engine of the four cycle type having a cylinder formed to provide an upper firing chamber and a lower air chamber with means to deliver a fuel charge to said firing chamber and a two step piston reciprocable in said cylinder chambers, a timed air admission means communicating with said air chamber adapted to admit air for scavenging purposes, a second timed variable capacity air admission means for admitting a measured quantity of air into said air chamber for use as a fuel mixture constituent, said piston having a port at its upper end to communicate with said firing chamber and passages leading to said port from said air chamber, and a piston pitman actuated timed valve means for said port.

2. In an internal combustion engine of the four cycle type having a cylinder formed to provide an upper firing chamber and a lower air chamber and a two step piston reciprocable in said cylinder chambers, a timed air admission means communicating with said air chamber adapted to admit air for scavenging purposes, a second timed variable capacity air admission means for admitting a measured quantity of air into said air chamber for use as a fuel mixture constituent, said piston having a port at its upper end to communicate with said firing chamber and passages leading to said port from said air chamber, a timed valve means for said port, a fuel pump means for injecting a combustible fuel constituent into said firing chamber, and means cooperative with said second air admission means adapted to automatically modify the fuel pump operation for maintaining a proportional rea-

tionship between the combustible fuel and air constituents of the delivered fuel mixture.

3. In an internal combustion engine of the four cycle type having a cylinder formed to provide an upper firing chamber and a lower air chamber with means to deliver a fuel charge to said firing chamber and a two step piston reciprocable in said cylinder chamber, an air intake means communicating with said air chamber, a valve to close said air intake means, timed means to open said valve during the descending power stroke of said piston for the intake into said air chamber of air for scavenging purposes, a second air intake means also communicating with said chamber, a second valve to close said second air intake means, regulatable means for governing the volume of air admissible through said second air intake means, timed means to open said second valve during the succeeding descending stroke of said piston for the intake of a measured quantity of air for use as a fuel mixture constituent, said piston having a port at its upper end to communicate with said firing chamber and passages leading to said port from said air chamber, and a timed valve means for said port.

4. In an internal combustion engine of the four cycle type having a cylinder formed to provide an upper firing chamber and a lower air chamber and a two step piston reciprocable in said cylinder chambers, an air intake means communicating with said air chamber, a valve to close said air intake means, timed means to open said valve during the descending power stroke of said piston for the intake into said air chamber of air for scavenging purposes, a second variable capacity air intake means also communicating with said air chamber, a second valve to close said second air intake means, timed means to open said second valve during the succeeding descending stroke of said piston for the intake of a measured quantity of air for use as a fuel mixture constituent, said piston having a port at its upper end to communicate with said firing chamber and passages leading to said port from said air chamber, a timed valve means for said port, a fuel pump means for injecting a combustible fuel constituent into said firing chamber, and means cooperative with said second air intake means adapted to automatically modify the fuel pump operation for maintaining a proportional relationship between the combustible fuel and air constituents of the delivered fuel mixture.

5. In an internal combustion engine of the four cycle type having a cylinder formed to provide an upper firing chamber and a lower air chamber and a two step piston reciprocable in said cylinder chambers, a timed air admission means communicating with said air chamber adapted to admit a maximum volume of air for scavenging purposes, a second variable capacity timed air admission means for admitting a variable volume of air into said air chamber for use as a fuel mixture constituent, said piston having a port at its upper end to communicate with said firing chamber and passages leading to said port from said air chamber, a timed valve means for said port, a fuel pump having a reciprocable plunger, means for reciprocating said plunger, and means

responsive to variation of air volume through said second air admission means for likewise varying the effective stroke of said fuel pump plunger.

6. In an internal combustion engine of the four cycle type having a cylinder formed to provide an upper firing chamber and a lower air chamber and a two-step piston reciprocable in said cylinder chambers, a timed variable capacity air admission for admitting a variable volume of air into said air chamber for use as a fuel mixture constituent, said piston having a port at its upper end to communicate with said firing chamber and passages leading to said port from said air chamber, a timed valve means for said port, a fuel pump having a reciprocable plunger, means for reciprocating said plunger, means responsive to variation of air volume through said second air admission means for likewise varying the effective stroke of said fuel pump plunger, said latter means comprising an enclosed diaphragm having a chamber on one side open to atmosphere and a chamber on the opposite side in communication with said second admission means, and means controlled by movements of said diaphragm for cooperation with said fuel pump plunger and its reciprocating means for the purposes mentioned.

7. In an internal combustion engine, a timed variable capacity air admission means for delivery of a variable volume of air for use as a fuel mixture constituent for admission with fuel to the engine firing chamber, a fuel pump means for injecting a combustible fuel constituent into said firing chamber, and means cooperative with said air admission means adapted to automatically modify the fuel pump operation for maintaining a proportional relationship between the combustible fuel and air constituents of the delivered fuel mixture.

8. In an internal combustion engine, a timed variable capacity air admission means for delivery of a variable volume of air for use as a fuel mixture constituent for admission with fuel to the engine firing chamber, a fuel pump having a reciprocable plunger, means for reciprocating said plunger, and means responsive to variation of air volume admitted through said air admission means for proportionally varying the effective stroke of said fuel pump plunger.

9. In an internal combustion engine, a timed variable capacity air admission means for delivery of a variable volume of air for use as a fuel mixture constituent for admission with fuel to the engine firing chamber, a fuel pump having a reciprocable plunger, means for reciprocating said plunger, means responsive to variation of air volume admitted through said air admission means for proportionally varying the effective stroke of said fuel pump plunger, said latter means comprising an enclosed diaphragm having a chamber on one side open to the atmosphere and a chamber on the other side in communication with said air admission means, and means controlled by the movements of said diaphragm for proportionally varying the effective stroke of said fuel pump plunger.

CARL C. OTTOSON.
